FIG 8.

James Alexander Hutchison

UNITED STATES PATENT OFFICE.

FRANCIS ALEXANDER HUTCHISON, OF WIMBLEDON PARK, ENGLAND.

DETACHABLE HEEL FOR BOOTS, SHOES, CLOGS, AND THE LIKE FOOTWEAR.

Application filed August 28, 1925, Serial No. 53,186; and in Great Britain December 12, 1924.

My invention relates to detachable, interchangeable and renewable heel-pads or heel-wearing-pieces, independent of, but attachable to the lower bottom of the permanent 5 heels of boots, shoes and the like footwear, comprising two plates of metal or other suitable material, slidingly interlocking, one of which is secured to the permanent heel and the other to the pad or wearing-piece.

10 The objects of my invention are, firstly, the total abolition of heel repair as now necessary; secondly, to provide means for connecting wearing-pieces only, to the bottom of the permanent heels of footwear, independent of and distinct from the heels themselves; thirdly, to provide means whereby wearing-pieces may be easily discarded when worn, and with the minimum of labour be instantly replaced by new in the 20 form of refills; fourthly, to provide a useful, cheap and efficient combination whereby the permanent heels of boots and shoes are protected from wear or damage; fifthly, to provide means whereby wearing-pieces separate from the heels, can be attached to the heels; to provide means whereby heels of any shape may be fitted with detachable, interchangeable and renewable wearing pieces.

30 I attain these objects by the novel combination of the devices and wearing-piece as illustrated in the accompanying drawing, in which—

Figure 1 shows, the upper side of the turned upper plate. Figure 2 shows, the upper side of the sliding lower plate. Figure 3, is a cross-section of the turned upper plate at the line A—A, with part locking device. Figure 4, a cross-section of the sliding lower plate at the line B—B, with part locking device. Figure 5, is a longitudinal section showing the sliding lower plate partially inserted into the channel on the turned upper plate, with locking device, at the lines 35 C—C and D—D. (Enlarged scale to show principle clearly.) Figure 6, shows, the sliding lower plate partially inserted into the channel on the turned upper plate with alternative locking device when indentations are from front to back of heel. Figure 7, an outside view of the front of a heel towards the instep arch or breast end, showing the combination as a whole; the channelled plate secured to the bottom of the heel and the sliding lower plate, with wearing-piece affixed, in position for use;

also showing the front enclosing flange and securing tag, on the front edge of the sliding lower plate. Figure 8, is an underneath view, (assuming the turned upper plate to be attached to the bottom of the heel) showing the method adopted for French or other specially shaped heels, with sliding lower plate partially inserted.

The plate 1, (called for identification purposes the "turned, upper plate") is attached to the bottom of the original heel of the boot, shoe, clog or the like, by screws, nails, rivets, spikes, or the like, which plate being shaped to the bottom of the heel, has its edges turned downwards and then inwards towards the centre of the plate, as shown on drawing Figs. 3 and 5, thus forming a horizontal rectangular channel on the inside of the outer edges on the underneath side when the plate is fixed, save only as to the edge opposite or towards the instep arch of the boot or shoe, as shown on drawing Figs. 1, 5 and 6. The outer edge of the plate 1, turned or worked as described, is square on the surface of the outer edge 2, to form a true face with the exterior of the heel 15, and the wearing-piece 12. That edge 5, of the plate 1, flush with the front of the heel towards the instep arch of the boot remains flat and ungrooved as aforesaid.

A second plate 6, of the same superficial shape as the plate just described, (for identification purposes called the "sliding, lower plate,") is kept perfectly flat within the dimensions of the heel, save as to one or more small indentations, 7 and 16, and 9 and 17, hereinafter described, and of slightly smaller general dimensions so that it may slide into the channel 4, provided on the turned upper plate 1, and exactly fit into the same as shown on drawing, Figs. 5, 6 and 8.

So as to prevent wet or dust from entering between the plates 1 and 6, and affecting the same, the sliding lower plate 6, is constructed with a turned up edge 8, outside the dimensions of the heel towards the instep arch, so as to entirely close over against the line 14, at which the lower face of the turned upper plate 1, and the upper face of the sliding lower plate 6, lie tightly and flatly the one against the other as shown on drawing, Figs. 5, 6 and 7.

To prevent the possibility of any movement of the sliding lower plate 6, both this plate and the turned upper plate 1, is in-

dented at some suitable position, preferably near the edges towards the instep arch. These indentations 7 and 16, and 9 and 17, being in exactly the same position on each of the plates 1 and 6, and being stamped and worked up the same way, slip one into the other and so form a lock, as will be seen from drawing Figs. 5 and 6. These indentations may be of varying number, shape and size, and be placed in any positions on the plates as may be most effective and when placed from the front towards the back of the heel, the back portion slopes to the level of the plates as more particularly shown on drawing Fig. 6,—9 and 17. This permits of the edges of the sliding lower plate 6, being easily inserted into the channel 4, and with a little pressure forced home.

The sliding lower plate 6, may also be constructed with a tag or turned up piece 10, at the extreme edge towards the instep arch, either the whole length of such edge or a part only, and drilled to permit of its being screwed, nailed or otherwise secured to the heel to prevent the possibility of the plate moving, as shown on drawing Figs. 5, and 7,—10.

Now, to the sliding lower plate 6, is secured by riveting, nailing, screwing, adhesive solution or other method, the leather, rubber or other material 12, intended to be the wearing surface of the heel, this material being so fixed and shaped to permit of the edges of the plate 6, being slipped into the channel 4, provided on the turned upper plate 1, as shown on drawing, Figs. 3, 5, 6 and 8,—4.

The passing of the sliding lower plate 6, into the channel 4, on the turned upper plate 1, combined with one or more of the locking devices, 7 and 16, 9 and 17, and 10, already referred to, makes the heel 15, the plates 1 and 6, and the wearing-piece 12, a uniform whole, as shown on drawing, Fig. 7, and provides a means of easily and quickly removing a worn wearing-piece 12, and renewing the same.

The sliding lower plates being made in uniform sizes with the turned upper plates, can be interchanged from one turned upper plate to another.

The shapes of the plates 1 and 6, are varied slightly for fitting special heels, such for instance as those known as French heels,

as shewn on drawing, Fig. 8. The turned upper plate 1, is exactly similarly constructed, but the channel 4, is partially filled on either side 13, to permit the sliding lower plate 6, being pressed home to the full extent of the channel 4, without there being any sideway movement, as shewn on drawing, Fig. 8.

The plates referred to in this specification may be so constructed to cover the whole of the bottom of the heel, or a part thereof only, or each or either of them may wholly or partially cover the bottom of the heel. Although for the purposes of clearly demonstrating the invention described in this specification, the turned upper or channelled plate is described as being attached to the heel of the boot or shoe, and the sliding lower plate with wearing-piece attached as being inserted therein, it should be clearly understood that either of the said plates may be attached to the heel or the wearing-piece, and when the channelled plate is attached to the wearing-piece, the channel is slipped over the edge of the other plate attached to the heel.

I claim:—

1. The combination of two plates of metal or other suitable material, and a heel-wearing-piece only, of wearable substance, one of the said plates having a rectangular channel on its outer edges save at the breast or instep arch end, and the other being perfectly flat save at the breast or instep arch end which is turned to form a protecting flange; either of which plates can be secured to the bottom face of the permanent heel of a boot, shoe or the like, and to the other can be affixed the said wearing-piece; both plates slidingly engaging and dis-engaging the one with the other, and having an internal locking device in the form of complementary indentations, automatic in action, one part in each plate, all substantially as set forth.

2. A drilled tag constructed to form an additional securing device for screwing or otherwise fixing to the permanent heel or wearing-piece, such tag being formed by the vertical extension of part or the whole of the protecting flange at the front of the insliding plate and flush with the front of the heel as in claim No. 1, and substantially as described.

FRANCIS ALEXANDER HUTCHISON.
